REFRIGERATED DISPLAY CABINET

Paul P. Omelianchuk, 6016 Concord, Minneapolis 24, Minn., and Dallas R. Humphrey, North St. Paul, Minn.; said Humphrey assignor to said Omelianchuk

Filed June 18, 1962, Ser. No. 70,572

Term of patent 14 years

(Cl. D80—11)

FIG. 1 is a front perspective view taken from one end of a refrigerated display cabinet embodying our new design;

FIG. 2 is a rear perspective view thereof taken from the end shown in FIG. 1; and

FIG. 3 is an elevational view of the end shown in FIGS. 1 and 2, the opposite end being a mirror image thereof.

We claim:

The ornamental design for a refrigerated display cabinet, substantially as shown and described.
